UNITED STATES PATENT OFFICE.

AUGUST H. JURK AND PAUL SYRACUSE, OF BUFFALO, NEW YORK.

ROTARY TOOTHBRUSH.

Application filed February 1, 1922. Serial No. 533,351.

To all whom it may concern:

Be it known that we, AUGUST H. JURK and PAUL SYRACUSE, citizens of the United States, residing at Buffalo, in the county of 5 Erie and State of New York, have invented certain new and useful Improvements in Rotary Toothbrushes; and we do hereby declare the following to be a full, clear, and exact description of the invention, such as 10 will enable others skilled in the art to which it appertains to make and use the same.

This invention has relation to tooth brushes and more particularly to an article of this character embodying a rotary brush 15 which is provided in a pair, the brushes being disposed to operate simultaneously upon opposite sides of the teeth and in a manner to obviate injury to the gums and insure a thorough cleansing of the teeth, particularly 20 in the spaces therebetween.

Other objects and advantages will be apparent and suggest themselves as the nature of the invention is understood.

While the drawings illustrate an embodiment of the invention it is to be understood that in adapting the same to meet different conditions and requirements, various changes in the form, proportion and minor details of construction may be resorted to 30 without departing from the nature of the invention.

Referring to the accompanying drawings forming a part of the application,

Figure 1 is a plan view of a rotary tooth brush embodying the invention,

Figure 2 is a front end view thereof, and Figure 3 is a section on the line 3-3 of Figure 1.

Corresponding and like parts are referred 40 to in the following description and designated in the several views of the drawings by like reference characters.

The device comprises a frame or casing 1 which is preferably of sectional formation 45 to facilitate the assembling of the parts. The frame or casing 1 preferably tapers throughout its length and has forwardly extending arms 2 which diverge and terminate in guards 3. Forwardly diverged 50 shafts 4 and 5 are journaled in the frame 1 and guards 3 and each is provided with a rotary brush 6 at its outer or forward end.

The inner or opposing portions of the brushes 6 are exposed, whereas the remaining portions are protected by means of the 55 guards 3 whereby to prevent injury to the lips or mouth in the use of the article. A sectional bearing 7 is disposed within the frame or casing 1 and receives the hubs 8 of gearwheels 9. The inner ends of the 60 shafts 4 and 5 are fitted to the hubs of the respective gearwheels so as to rotate therewith. The gearwheels 9 are in meshing relation at all times so that motion imparted to one is transmitted to the other, whereby 65 both brushes 6 are rotated simultaneously in reverse directions. A handle 10 is applied to the frame or casing 1 and receives a flexible shaft 11 which is connected to one of the gear wheels 9 whereby to rotate the 70 brushes when the device is in operation. The shaft 11 derives motion from an electric motor 12 which may be suitably disposed and which is adapted to be plugged into a suitable connection of a current supplying 75 conductor.

The diverging arrangement of the shafts 4 and 5 result in a compact structure and arrangement and admits of the proper spacing of the brushes 6 whereby they are adapted to operate upon opposite sides of the teeth as indicated most clearly in Figure 1.

What is claimed is:

1. A rotary tooth brush having a first brush and a second brush to simultaneously 85 engage the teeth at opposite surfaces thereof, a shaft carrying one of said brushes, a casing tapering inwardly away from the brushes and carrying said shaft, a handle extending from the smaller end of the casing in line with said shaft, and a shaft diverging from the first shaft carrying the other brush and geared to the first shaft in said casing.

2. A rotary tooth brush having a first 95 brush and a second brush to simultaneously engage the teeth at opposite surfaces thereof, a shaft carrying one of said brushes, a casing tapering inwardly away from the brushes, a bearing within said 100 casing adjacent its larger end, a gear wheel having a hub journaled in said bearing and carrying said shaft, a handle extending from the smaller end of the

casing in line with said shaft, a shaft diverging with relation to the first shaft and carrying the other brush, and a gear wheel on the second shaft having its hub journaled with said bearing, and the second mentioned gear wheel being in mesh with the first mentioned gear wheel.

In testimony whereof we affix our signatures in presence of two witnesses.

AUGUST H. JURK.
PAUL SYRACUSE.

Witnesses:

CHARLES J. WOLTZ,
STANLEY LACNY.
